(57) CLAIM

The ornamental design for a head cover, as shown and described.

DESCRIPTION

FIG. 1 is a top, front and right side perspective view of a head cover showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines in the drawings represent conventional stitching.
